Attorney

UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING MACHINE.

Application filed January 29, 1921. Serial No. 440,836.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to a typewriting 10 machine having a carriage which is fed step by step towards the left, and an object of the invention is to provide improved means to facilitate the positioning of the carriage to begin a new paragraph.

15 A feature of the invention consists in the provision of manipulative means within easy access of the operative, whereby, after the carriage is returned to the extreme right-hand side of the machine, it may be quickly 20 advanced to begin a new paragraph at a predetermined letter-space. Preferably, the manipulative means, comprising a tabulator-key, which controls the position of the carriage, is mounted on said carriage.

25 Other features and advantages will hereinafter appear.

In the accompanying drawings,

Figure 1 is a sectional right-hand elevation of a portion of the carriage, showing 30 parts of the escapement mechanism.

Figure 2 is a view similar to Figure 1, but shows the positions of parts when the tabulator-key is depressed.

Figure 3 is a top plan view of a portion 35 of the carriage and the main frame.

Figure 4 is a perspective view of the right-hand portion of the carriage and the main frame, looking from the rear.

Figure 5 is a detail perspective view of 40 the stop on the carriage.

The platen 1 is journaled as usual in a carriage 2 and is supported therein by the usual platen axle 3. The carriage is mounted for movement as usual on the main frame 45 of the machine, a portion of which is shown at 4, the carriage being fed in letter-space movements by a spring-drum 5 and through the usual escapement mechanism under the control of the usual type-keys (not shown), 50 said escapement mechanism including the usual escapement wheel 6, escapement pinion 6^a and feed-rack 7, the latter adapted to engage the pinion 6^a in the normal operation of the machine, whereby the carriage is fed.

55 After the carriage has been fed leftward

for writing a line, it may be returned a full distance to the right where it may be arrested against the usual margin-stop (not shown), and the usual space-bar may then be operated to step the carriage along to a 60 position where a new paragraph is to begin. This involves a number of operations of the space-bar and consumes considerable time.

The present invention seeks to provide a 65 more convenient and rapid means for positioning the carriage, whereby to begin a new paragraph; and, for this purpose, there is preferably provided fixed and movable stops with means for setting the movable stop 70 into the path of the fixed stop, so that the carriage may be quickly positioned at the letter-space determined upon. Preferably, the fixed stop is carried by the main frame, and the movable stop is carried by the carriage. The fixed stop is shown at 8 (Figures 1, 2 and 4), and is adapted to co-operate with a movable stop 9 which is carried by a hexagonal bar or shaft 10 pivoted in the right side frame 11 of the carriage. The 80 inner end of said bar is carried by a bracket 12, which may be adjustably secured along the carriage frame by screws 12^a (Figure 3) which may engage any of a series of holes 12^b.

The stop 9 is shown in detail in Figure 5, and has a hexagonal hole through its downwardly projecting sides through which the bar 10 passes, so that when said bar is rocked the stop 9 is moved from the position shown 90 in Figure 1 to the position shown in Figure 2, when it is in the path of the fixed stop 8. A spring 10^a connected to stop 9 and to bracket 12 acts to hold the stop and therefore bar 10 in normal position. In order to 95 set the stop 9, manipulative means, in the form of a key-lever 13, is provided, said lever being pivoted loosely on the platen axle 3, and having a finger-piece or key 14 at one end, its opposite end being slotted to engage a pin 15 carried by an irregularly-shaped member 16 mounted on the bar 10. Rocking of the lever 13 will, therefore, act to rotate the bar 10 and said stop 9. To release the carriage from the escapement mechanism during a tabulating operation, the lever 13 has a bent-over lip 17, which engages an arm 18^a of a lever 18 to swing the latter about its pivot 19 and raise the rack 7 out of engagement with the pinion 6^a. The 110

arm 18^a has an enlargement 21 with which the lip 17 engages to limit the movement of the lever 13.

The lever 18 may be independently rocked 5 by a finger-piece or carriage-release key 22, as is usual in machines of this character. When the lever 13 is released, the spring 10^a, connected with the stop 9, returns the lever to normal position, and, during the first part 10 of the return movement, the lip 17 is moved away from the enlargement 21, permitting the rack to re-engage the pinion before the stop 9 is moved to normal position out of the path of the stop 8. The carriage is, 15 therefore, held at the predetermined letter-space to which it has been positioned by contact of the stops 8 and 9.

It will be understood that the hexagonal shaft 10 extends through circular holes 23 20 in the bracket 12 which forms a bearing for the inner end of said shaft, as hereinbefore stated. The stop 9 is embraced by the bracket and is slidable lengthwise of the shaft 10 with the return spring 10^a to be adjusted according to the length of indentation of the paragraph.

Variations may be resorted to within the scope of the invention, and portions of the improvements may be used without others.

30 Having thus described my invention, I claim:

1. The combination of a main frame, a platen-carriage thereon, escapement mechanism, a feed-rack on said carriage to engage 35 said escapement mechanism, a spring-drum to propel said carriage, a rack-supporting lever, a release key-lever to engage said rack-supporting lever to disengage said rack, another key-lever to engage said sup- 40 porting-lever to disengage the rack, a stop on said carriage operable by the second-named key-lever, and a fixed stop on the main frame.

2. The combination of a main frame, a 45 platen-carriage thereon, escapement mechanism, a feed-rack on said carriage to engage said escapement mechanism, a spring-drum to propel said carriage, a rack-supporting lever, a release key-lever pivoted on said car- 50 riage to engage said rack-supporting lever to disengage said rack, an arm on said rack-supporting lever, another key-lever pivoted on said carriage and engaging with said arm to operate said supporting lever and 55 disengage said rack, a stop on said carriage operable by the second-named key-lever, and a fixed stop on the main frame.

3. The combination of a main frame, a platen-carriage thereon, escapement mecha- 60 nism, a feed-rack on said carriage to engage said escapement mechanism, a spring-drum to propel said carriage, a rack-supporting lever, a release key-lever to engage said rack-supporting lever to disengage said 65 rack, an arm on said rack-supporting lever,

another key-lever engaging said arm to operate the latter, a stop on said carriage operable by the second-named key-lever, a fixed stop on the main frame, and means on said arm to limit the movement of the 70 second-named lever.

4. The combination of a main frame, a platen-carriage thereon, escapement mechanism, a feed-rack on said carriage to engage said escapement mechanism, a spring-drum to propel said carriage, a rack-supporting lever, a release key-lever pivoted on said carriage to engage said rack-supporting lever to disengage said rack, an arm thereon, another key-lever pivoted on said carriage 80 to engage the arm of said supporting-lever to operate the latter to disengage said rack, a rock-shaft on said carriage operable by the second-named key-lever, an adjustable stop on said rock-shaft and operable there- 85 by, and a fixed stop on the main frame.

5. The combination of a main frame, a platen-carriage thereon, escapement mechanism, a feed-rack on said carriage to engage said escapement mechanism, a spring-drum to propel said carriage, a rack-supporting lever, a release key-lever to engage said rack-supporting lever to disengage said rack, another key-lever to engage said supporting-lever to disengage said rack, a rock-shaft on 90 said carriage operable by the second-named key-lever, an adjustable stop on said rock-shaft and operable thereby, and a fixed stop on the main frame.

6. The combination of a main frame, a platen-carriage thereon, tabulating mechanism comprising a fixed stop and a co-operative stop, a rock-shaft extending in the direction of travel of said carriage, the co-operative stop being mounted on said rock-shaft, and a bracket to support one end of the rock-shaft, said bracket embracing the co-operative stop and being settable lengthwise of the rock-shaft to adjust the co-operative stop to various positions.

7. The combination of a main frame, a platen-carriage thereon, tabulating mechanism comprising a fixed stop on said frame, a co-operative stop on said carriage, a rock-shaft mounted on said carriage and extending in the direction of its travel, the co-operative stop being mounted on said shaft, a bracket to support one end of the rock-shaft, said bracket embracing the co-operative stop and being settable lengthwise of the shaft to adjust the co-operative stop to various positions, and means to hold the bracket in place on said carriage.

8. The combination of a main frame, a platen-carriage thereon, escapement mechanism, a feed-rack on said carriage to engage the escapement mechanism, a spring-drum to propel said carriage, a rack-supporting lever, a tabulator key on said carriage to engage said rack-supporting lever to dis-

- engage said rack, a fixed stop on the frame, a shaft on said carriage to be rocked by said tabulator key, a stop on said shaft to be moved into the path of said fixed stop, and a return spring for said shaft.
9. The combination of a main frame, a platen-carriage thereon, escapement mechanism, a feed-rack on said carriage to engage the escapement mechanism, a spring-drum to propel said carriage, a rack-supporting lever, a tabulator key on said carriage to engage said rack-supporting lever to disengage said rack, a fixed stop on said frame, a shaft on said carriage to be rocked by said tabulator key, a stop on said shaft to be moved into the path of the fixed stop, the movable stop being adjustable lengthwise of the shaft, and means to hold the movable stop in its adjusted position.
10. The combination of a main frame, a platen-carriage thereon, escapement mechanism, a feed-rack on said carriage to engage the escapement mechanism, a spring-drum to propel said carriage, a rack-supporting lever, a tabulator key on said carriage to engage said rack-supporting lever to disengage said rack, a fixed stop on said frame, a shaft on said carriage to be rocked by said tabulator key, a stop on said shaft to be moved into the path of said fixed stop, and a bracket to support one end of said shaft, said bracket embracing the stop on the rock-shaft, and said bracket being adjustable lengthwise of the shaft to adjust the stop associated therewith to various positions.
11. The combination of a main frame, a platen-carriage thereon, escapement mechanism, a feed-rack on said carriage to engage the escapement mechanism, a spring-drum to propel said carriage, a rack-supporting lever, a tabulator key on said carriage to engage said rack-supporting lever to disengage said rack, a fixed stop on said frame, a shaft on said carriage to be rocked by said tabulator key, a stop on said shaft, the last-named stop being rotatable with said shaft into the path of the fixed stop, the rotatable stop being slidale lengthwise of said shaft, a bracket to support one end of said shaft, said bracket being adjustable lengthwise of the shaft to set the rotatable stop in various positions, and means to secure the bracket in place on the carriage.
12. The combination of a main frame, a platen-carriage on said frame, tabulating mechanism comprising a fixed stop and a co-operative stop, actuating means to move the co-operative stop into the path of the fixed stop, a bracket associated with the co-operative stop, said bracket being settable in either direction of the travel of said carriage to adjust the co-operative stop to various letter-space positions, and means to engage said bracket to retain the co-operative stop in its adjusted position.
13. The combination of a main frame, a platen-carriage on said frame, tabulating mechanism comprising a fixed stop on said frame and a co-operative stop on said carriage, actuating means to move the co-operative stop into the path of the fixed stop, a bracket associated with the co-operative stop, said bracket being settable on said carriage to adjust the co-operative stop to various letter-space positions, and holding means for the bracket.
14. The combination of a main frame, a platen-carriage on said frame, tabulating mechanism comprising a fixed stop and a co-operative stop, actuating means comprising a rock-shaft extending lengthwise of said carriage to move the co-operative stop into the path of the fixed stop, and a bracket for said rock-shaft and associated with the co-operative stop, said bracket being settable lengthwise of said shaft to adjust the co-operative stop to various letter-space positions.
15. The combination of a main frame, a platen-carriage on said frame, tabulating mechanism comprising a fixed stop on said frame and a co-operative stop on said carriage, actuating means comprising a rock-shaft extending lengthwise of said carriage to move the co-operative stop into the path of the fixed stop, a bracket for said rock-shaft, said bracket being associated with the co-operative stop, and said bracket being settable on said carriage and lengthwise of said shaft to adjust the co-operative stop to various letter-space positions, and holding means for said bracket.
16. The combination of a main frame, a platen-carriage on said main frame, tabulating mechanism comprising a fixed stop and a co-operative stop, actuating means for the co-operative stop, a bracket associated with the co-operative stop, a spring between the bracket and the co-operative stop to return the latter to normal, said bracket being settable to adjust the co-operative stop to various letter-space positions, and means engaging the bracket to retain the co-operative stop in adjusted position.
17. In tabulating mechanism for type-writing machines, the combination of a fixed stop and a co-operative stop, a supporting bar for said co-operative stop, a bracket to support said bar, said bracket being associated with the co-operative stop, and said bracket being settable to adjust the co-operative stop to various letter-space positions, and means to actuate said supporting bar to move the co-operative stop into the path of the fixed stop.
18. The combination of a main frame, a carriage thereon, a platen rotatably mounted on the carriage, escapement mechanism, a rack on the carriage to engage the escapement mechanism, a spring-drum to propel

the carriage, a release-key journaled on the axis of the platen at one end of the platen, a second release-key also journaled on the axis of the platen, and a paragraph-stop controlled by said second key.

19. The combination of a main frame, a platen-carriage thereon, escapement mechanism, a feed-rack on said carriage to engage said escapement mechanism, a spring-
10 drum to propel said carriage, rack-supporting levers, a key-release-lever for disengaging the rack from the escapement

mechanism, one of said rack-supporting levers comprising a rack-supporting arm, an arm for engaging the key-release-lever and a third arm extending laterally from said second-mentioned arm, and carriage-stop mechanism operable on said laterally-extending arm to disengage the rack from the escapement mechanism.

ALFRED G. F. KUROWSKI.
